Chase, Dent & Mayers

UNITED STATES PATENT OFFICE.

ALLAN MACBETH, OF PARIS, FRANCE, ASSIGNOR TO STE THE DUNLOP RUBBER CO. LIMITED, OF PARIS, FRANCE.

PETROL-TANK AND THE LIKE.

1,397,833.

Specification of Letters Patent. Patented Nov. 15, 1921.

Application filed August 22, 1918. Serial No. 251,004.

To all whom it may concern:

Be it known that I, ALLAN MACBETH, a subject of the King of Great Britain, residing in Paris, France, have invented certain new and useful Improvements in 5 Petrol-Tanks and the like, of which the following is a specification.

The present invention has for its object a petrol tank for aerial apparatus combined 10 in such a way as to avoid leakages despite perforations produced by projectiles of small caliber, such as rifle bullets, machine gun bullets or shrapnel bullets or by small shell splinters.

15 It consists broadly in covering the metal tank externally with a covering having a layer of raw natural rubber or unvulcanized caoutchouc which, in case of leakage dissolves in contact with the petrol and 20 forms a soft substance capable of automatically stopping up the perforation.

The description now about to be given with reference to the accompanying drawings given by way of example relates to a 25 tank constructed according to the invention, and to modifications, which will enable the peculiarities and advantages of this invention to be thoroughly understood.

Figure 1 shows the whole of a tank in 30 transverse section.

Figs. 2 and 3 relate to the walls constructed according to the modifications.

In the case of Fig. 1, there is applied to the whole of the surface of the metal 35 tank *a*—

(1) A primary sheet of fabric *b* impregnated with a solution of vulcanizable rubber;

(2) Upon the primary sheet *b* a layer *c* of natural crude rubber or unvulcanized 40 caoutchouc;

(3) Upon the layer of caoutchouc *c* a second sheet of fabric *d* similar to the primary sheet *b*.

The two sheets of fabric *b* and *d* have for 45 their object to hold the caoutchouc *c* in such a way as to form a mattress or covering for the tank *a*.

This lining has naturally in it the necessary openings for the passage of objects or 50 parts which project beyond the tank *a*, such as the filling plug, level indicator, etc.

After it has been applied the covering constructed as has just been described is subjected to the operation of vulcanization, the

object of which is to render the two sheets 55 of fabric *b* and *d* rigid and to cause the first one to adhere closely to the wall of the reservoir *a*. The layer *c* contained between the two sheets of fabric does not undergo any change and remains attackable by the petrol. 60

In case of perforation, the petrol commences to flow, the first oozings dissolve the nonvulcanized caoutchouc *c* which softens, spreads out between the two sheets of fabric and automatically stops up the perforation. 65

It should be noted that the two sheets of fabric *b* and *d* play a part in the stopping up of the openings. As a matter of fact when a bullet passes through, the threads of these sheets of fabric are broken but they 70 are not carried away by the bullet they thus form a screen which serves for the support of the plastic substance of the caoutchouc *c* and facilitate the agglomeration thereof.

The two modified constructional forms of 75 the composite covering of rubber cloth and rubber which is not vulcanized, described above, concern principally the replacement of the sheet of fabric by caoutchouc, as well as the arrangements which permit of the 80 softening of the different layers of the protecting envelop.

In the first, shown in Fig. 2, the rubber coated fabrics previously placed on either side of the sheet of unvulcanized rubber are 85 replaced by sheets of vulcanized rubber.

The metal wall of the reservoir is shown at *A*, a first vulcanized sheet *B* of from 2 to 3 millimeters in the thickness is applied to this wall, then upon this sheet is placed 90 the non-vulcanized sheet *C*, which may be from 7 to 10 millimeters thick. Finally the whole is covered over by the vulcanized sheet *D* from 2 to 3 millimeters thick.

It will be seen that the wall thus constructed is always based upon the same principle as that above described but by the substitution of the sheets of rubber *C* and *D* which surround the non-vulcanized sheet greater elasticity and suppleness are obtained, 100 which gives to the whole when it is necessary a more efficacious protection.

The different layers of caoutchouc may be stuck together cold, but the vulcanization gives to the whole protecting mass more 105 homogeneity. In the course of this operation, the sheet *c* which does not contain any sulfur, or very little of it, does not undergo

so to speak the influence of the vulcanization; but the heat changes the consistency of this sheet in advantageous manner, communicating to it a maximum of elasticity.

5 In the second modification shown in Fig. 3, there is still a wall constructed of several layers according to the invention, but between the surface of the reservoir and the first sheet of the covering there is left an 10 empty space of some millimeters so as to separate the two parts (metal and covering) when a shock is produced. The distance between these two parts is kept regular in all directions by means of small 15 distance pieces G arranged on the metal wall or on the india rubber wall. The same result may be obtained by means of undulations. These undulations are provided on the metallic surface of the tank and are 20 composed of a fish-bellied plate, the outline of which is well known. In this constructional form it is well to render impermeable to hydrocarbons the surface of the caoutchouc in contact with the liquid when the 25 reservoir has been perforated.

This impermeability is obtained by means of coatings which are insoluble or only very slightly soluble in hydrocarbons, such as 30 gutta-percha, balata, gum lac or other similar products, which are applied to the inner surface of the covering.

In the constructional example shown in Fig. 3, the metal wall is at A, at E are spread two layers of gum lac, at F is a 35 thickness of gutta-percha or balata of 2 millimeters. Then come as usual the two vulcanized thicknesses B, D having between them the unvulcanized rubber C.

Another method of effecting the separation consists in interposing between the outer surface of the reservoir and the inner surface of the protective envelop lubricants such as talc plumbago, etc. This latter method which yields good results, has also 45 the advantage of reducing the space occupied by the reservoir for a given capacity.

It must be understood that the above directions are given by way of example only and that it is possible to employ at will the 50 various improvements described in combination with one or other of the methods of carrying out the invention described or to vary the proportions of the thicknesses according to the different cases of application.

55 What I claim and desire to secure by Letters Patent of the United States is:—

1. A reservoir for hydrocarbon liquid comprising a layer of non-vulcanized rubber soluble in the hydrocarbon liquid, and two layers of material relatively insoluble in 60 said liquid, said soluble rubber layer being contained between said insoluble layers.

2. A reservoir for liquid fuel comprising a layer of non-vulcanized rubber and two layers of vulcanized rubber, said layer of 65 non-vulcanized rubber being contained between the vulcanized layers of rubber.

3. A petrol reservoir having an outer covering comprising a layer of unvulcanized rubber and two sheets of vulcanized rubber 70 fabric between which said layer is confined.

4. A reservoir for liquid fuel comprising a metallic wall and layers of material which are relatively insoluble in the liquid having between them a layer of material which is 75 soluble in the liquid and means for insulating the metallic wall of the reservoir from contact with the said layers of material.

5. A reservoir for liquid fuel comprising a metallic wall and layers of material which are relatively insoluble in the liquid having 80 between them a layer of material which is soluble in the liquid and means for insulating the metallic wall of the reservoir from contact with the said layers of material, 85 said means comprising a means for spacing said layers from the wall of the reservoir.

6. A reservoir for liquid fuel comprising layers of material which are relatively insoluble in the liquid having between them a layer of material which is soluble in the liquid and means for spacing said layers from the wall of the reservoir and a material filling the intervening space. 95

7. A reservoir for liquid fuel comprising layers of material which are relatively insoluble in the liquid having between them a layer of material which is soluble in the liquid and means for spacing said layers 100 from the wall of the reservoir and a material filling the intervening space, said material being insoluble in the liquid.

In witness whereof I have hereunto signed my name in the presence of two subscribing 105 witnesses.

ALLAN MACBETH.

Witnesses:

JOHN F. SIMONS,
HENRI CARTIER.
